UNITED STATES PATENT OFFICE.

NICK MAGGIO, OF BROOKLYN, NEW YORK.

TRUSS.

1,386,886.

Specification of Letters Patent. Patented Aug. 9, 1921.

Application filed October 9, 1920. Serial No. 415,940.

To all whom it may concern:

Be it known that I, NICK MAGGIO, a subject of the King of Italy, residing at Brooklyn, in the county of Kings and State of New York, have invented certain new and useful Improvements in Trusses, of which the following is a specification.

This invention relates to certain new and useful improvements in trusses and has for one of its objects to provide a truss having a fabric section embracing the lower portion of the abdomen and secured to the body by a waist belt and leg straps carried thereby.

A further object of the invention is to provide a truss wherein the fabric body engaging section carries a removable elastic element inclosing the upper portion of the abdomen to constitute a supporting brace for that part of the body.

A still further object of the invention includes the provision of certain materials of which the truss is constructed so that the body of the wearer is entirely free from engagement by any metallic parts of the truss, thus insuring against abrasions during wear.

With the above and other objects in view that will appear as the nature of the invention in better understood, the same consists in the novel construction and association of parts to be hereinafter more fully described and then claimed.

In the drawings forming a part of this application and to which reference is had by like characters designating corresponding parts throughout the several views:

Figure 1 is a front perspective view of a truss constructed in accordance with the present invention.

Fig. 2 is a rear perspective view of the truss.

Fig. 3 is a vertical cross-sectional view taken on the line III—III of Fig. 1 showing the flexible body engaging shield carried by the upper end of the truss.

Fig. 4 is a detailed sectional view taken on the line IV—IV of Fig. 2 showing the metallic shell inclosed by the pad, and

Fig. 5 is a detailed sectional view showing the snap fastener connection between the body of the truss and the elastic band.

Referring more in detail to the accompanying drawings there is illustrated a truss embodying an abdomen engaging portion 1, the outer face of which is formed of a soft and smooth material as silk, as shown in Fig. 1, while the inner abdomen engaging face there-

of is formed of velvet or like material as shown in Fig. 2. The forward portion of the truss is of the usual design having depending front sections 2 while the edges of the front part of the truss carry rear belt sections 3 and 4, the inner faces of which are of velvet while the outer faces are formed of leather, shown respectively in Figs. 1 and 2. The overlapping ends of the belt sections 3 and 4 are adjustably connected by the buckle 5 as shown in Fig. 2.

One of the pads associated with the body 1 of the truss is shown in Fig. 4, the same embodying a metallic shell 6 of proper design inclosed by the outer layer of silk and the inner layer of velvet with the two plies of material surrounding the shell secured as by stitching 7.

To assist the waist belt sections 3 and 4 in properly retaining the truss upon the body of the wearer, a pair of crotch straps 8 and 9 are secured to the depending front portions 2 and are adapted for passage between the legs as shown in Fig. 1 with the free ends thereof adjustably connected to the buckles 10 carried by the tabs 11 projecting from the body of the truss. The leg straps 8 and 9 where the same contact the inner sides of the legs are formed of velvet with the tops of the straps formed of leather for engagement with said buckles.

An elastic abdomen supporter 12 has the lower edge thereof provided with male members 13 of snap fasteners, shown more clearly in Fig. 5, that are adapted for engagement in sockets 14 carried by the leather strap 15 secured to the upper edge of the truss 1, openings being provided in the truss to accommodate the passage of the snap fastener elements 13. As shown in Figs. 1 and 2, the lower edge of the elastic band or shield 12 is curved coincident to the upper edge of the body 1 of the truss while the upper edge of said band is preferably cut upon a straight line.

In positioning the truss upon the body, the desired tension at the waist line is controlled by the buckle connection 5 between the straps 3 and 4. In order to prevent rising of the truss and to properly position the same with the pads engaging the affected parts of the body, the leg straps 8 and 9 after being passed between the legs have the free ends thereof attached to the buckles 10 and by placing the desired tension on said straps, a downward pull of the body of the truss

against the waist band sections is accomplished, thereby properly holding the truss supported on the body. The elastic band 12 extending above the truss supports that part 5 of the abdomen usually exposed, and while limiting movements thereof will operate to support the abdomen and assist the truss in performing its usual functions. For sanitary purposes, as in cleaning the fabric elements of the truss it is possible to completely 10 detach the elastic band 12 therefrom by disconnecting the male and female members of the snap fasteners and it is also to be understood that elastic bands of different designs 15 may be provided for detachable engagement with the truss.

While there is herein shown and described the preferred embodiment of the invention, it is to be understood that minor changes are 20 contemplated as will fall within the scope of the invention as hereinafter claimed.

What is claimed as new is:

1. In combination with a truss, a detachable elastic abdomen supporting band se-.

cured to the upper edge thereof, the lower 25 edge of said band being cut upon a relatively straight line and curved coincident to the upper edge of said truss, the upper edge of said band tapering toward its edges from its center point of greatest height.

2. A truss of the type described comprising a body part, waist belt sections carried thereby, a belt section secured to the upper edge of the body of the truss upon the outer face thereof, members of separable fasteners carried by said belt section, the upper edge of the body of the truss having openings registering with said separable fastener members, an elastic abdomen supporting band associated with said truss body and other members of said separable fasteners secured to the lower edge of said elastic band engaging with said first named fastener members for attaching the elastic band to the body of the truss.

45 In testimony whereof I affix my signature.

NICK MAGGIO
